UNITED STATES PATENT OFFICE.

EDWARD C. SCHINKE, OF ST. LOUIS, MISSOURI, ASSIGNOR TO THE ACCOUNTOGRAPH COMPANY, OF ST. LOUIS, MISSOURI, A CORPORATION OF MISSOURI.

CALCULATING MACHINE.

Application filed November 6, 1920. Serial No. 422,165.

This invention relates to improvements in calculating machines and more particularly to a means for locking and unlocking the calculating mechanism.

Prior to this invention, calculating machines have been provided with denominational carriages movable step by step to provide for the transmission of movement to total wheels of different orders. For example, an accumulator has been provided with an actuator and a denominational carriage movable step by step to change the denominational relation of the actuator to the accumulator, thereby providing for the transmission of movement to a series of total wheels of different orders. The actuator just referred to may be a rotary master wheel, and it may be carried by the denominational carriage so as to advance one step in response to each operation of the numeral keys. In the specific structure hereafter described, the denominational carriage is driven by the traveling platen carriage of an ordinary typewriter, and the accumulator is actuated through the medium of a rotary master wheel carried by the denominational carriage. The master wheel is provided with gear teeth and it advances step by step so as to successively mesh with accumulator wheels of different orders. I will hereafter refer to this specific structure with the understanding that the invention comprehends variations and modifications within the scope of the claims hereunto appended.

The machine herein disclosed may be considered an improvement over the machine shown by Patent No. 1,358,114, Schinke and Sutherland, Nov. 9, 1920, and this earlier patent may be referred to for a more complete description of the operation of the machine.

One object of the invention is to prevent operation of the calculating mechanism while the denominational carriage is in its starting position, i. e., when the master wheel is in a position at one side of the accumulator.

Another object is to prevent operation of the calculating mechanism while the denominational carriage is moving from one denominational position to another, thereby preventing rotation of the master wheel

while it occupies an intermediate position between two denominational wheels of the 55 accumulator, or while it is in mesh with both of said denominational wheels. With this object in view, I have herein disclosed a simple means whereby the calculating mechanism is locked in response to each forward step of the denominational carriage on which the master wheel is mounted, and I have shown a means for unlocking the calculating mechanism when the master wheel is properly meshed with the accumulator 60 wheel to be driven thereby. This is an important feature of the invention, for it positively prevents accidental operation of the master wheel while the latter is advancing from one denominational position to another. 65

A further object is to prevent operation of the calculating mechanism while the denominational carriage is returning to its starting position, thereby preventing accidental premature operation of the master 70 wheel. 75

Under some conditions, which will be hereinafter pointed out, the denominational carriage is quickly shifted toward its starting position and then stopped in an intermediate position. In this event, the locking means herein shown will prevent operation of the calculating mechanism while the carriage is moving toward its starting position, and thereafter upon the completion of the next forward step of said carriage, the calculating mechanism is automatically unlocked. 80

More specifically stated, an object is to 85 provide a simple means for accomplishing all of the foregoing results, which may be briefly pointed out as follows:

The calculating mechanism is locked when the denominational carriage is in its starting position, or "home" position, also during each forward step of said carriage while the master wheel is moving from one denominational position to another. The calculating mechanism is also locked when the 90 carriage is moving toward its starting position, and it remains in a locked condition until a forward motion is imparted to the carriage. In other words, the calculating mechanism is locked at all times, excepting 95 the periods when the master wheel is proper- 100 105

ly positioned for operation of a selected ac-
cumulator wheel.

Fig. I is a side elevation, partly in sec-
tion, illustrating a typewriter calculating
mechanism, adapted to be actuated by the
numeral keys and platen carriage of the
typewriter.

Fig. II is a top or plan view of the cal-
culating mechanism.

10 Fig. III is a rear elevation of the type-
writer, showing a portion of the means for
transmitting motion from the platen car-
riage to the denominational carriage.

15 Fig. IV is a fragmentary view, partly in
section, illustrating a part of the means for
transmitting motion from the platen car-
riage.

Fig. V is a section taken approximately
on the line V—V, Fig. III.

20 Fig. VI is a fragmentary view illustrating
a portion of the accumulator and showing
the master wheel whereby motion is trans-
mitted to the accumulator.

Fig. VII is a fragmentary view showing
25 a portion of the platen carriage and a por-
tion of the means for transmitting move-
ment therefrom.

Fig. VIII is an enlarged detail view of
the lock controlling devices, showing the
30 positions occupied by said devices when the
denominational carriage is in its starting
position, or "home" position.

Fig. IX is a view similar to Fig. VIII,
showing the positions of the lock controlling
35 devices when the denominational carriage is
permitted to return to an intermediate posi-
tion.

Fig. X is a view similar to Fig. VIII,
showing the position of the lock controlling
40 devices when the denominational carriage
occupies its extreme forward position.

Fig. XI is a view similar to Fig. VIII,
showing the positions of the lock controlling
45 devices when the master wheel is positioned
to actuate the accumulator.

Briefly stated, the machine about to be de-
scribed is a calculating attachment for type-
writers, and it is adapted for use with ordi-
nary typewriting machines now on the mar-
50 ket. The numbers to be added are written
by the typewriter and the total is indicated
by an accumulator. The accumulator here-
after described comprises a series of total
55 wheels of different orders, and motion is
transmitted from a master wheel to the total
wheels. Either the master wheel or the ac-
cumulator must travel step by step in re-
sponse to the key operations, so as to change
the denominational relation of the master
60 wheel to the accumulator. The master wheel
is therefore splined to a rotary shaft and
carried by a master wheel carriage, or de-
nominational carriage, adapted to travel in
unison with the platen carriage of the type-
65 writer. The master wheel is rotated through

the medium of the numeral keys of the type-
writer. To avoid unnecessary illustration
and description, I have not shown various
details of construction which are old and
well known in this art, and which are ordi-
narily found in calculating attachments for
typewriters.

The accumulator.

I do not deem it necessary to point out
all of the details of construction of an ac-
cumulator, such devices being old and well
known in the art, and no claim is herein
made for an accumulator per se. To illus-
trate certain features of the invention, I
have shown in a more or less conventional
manner an accumulator A (Figs. I, II, and
VI). This accumulator comprises a hous-
ing 1 mounted at the front of the machine
and provided with total indicating wheels
2 which may be viewed through a sight open-
ing in the top of the housing, and trans-
mission wheels 3 located below and meshing
with the total wheels 2. B designates a
master wheel splined to a rotary shaft 4
and adapted to mesh with the transmission
wheels 3. The master wheel is adapted
to travel step by step, longitudinally of the
shaft 4, so as to successively mesh with the
transmission wheels 3, which are shown most
clearly in Figs. I and VI. The master
wheel shaft 4 is rotated through the medium
of the numeral keys, as will be hereafter de-
scribed.

The master wheel carriage, or denomina-
tional carriage, comprises a rack bar 5 pro-
vided with lateral extensions 6 slidably
mounted on a stationary horizontal rod 7,
and an arm 8 extending forwardly from the
rack bar 5, said arm 8 having a forked end
which extends into a circular groove 9
formed in the periphery of the master wheel
hub. 10 designates a restoring spring (Fig.
II) connecting the master wheel carriage to
a stationary post 11. This spring tends to
retain the master wheel carriage in its start-
ing position (shown in Fig. II) wherein one
of the extensions 6 of said carriage engages
an abutment 12.

Feeding the master wheel carriage.

To change the denominational relation of
the master wheel to the accumulator, the
master wheel is movable step by step along
the shaft 4, and this movement is obtained
by transmitting power from the platen car-
riage of the typewriter to the master wheel
carriage. The rack bar 5, forming part of
the master wheel carriage, meshes with a
sector 13 (Figs. I and II), said sector being
fixed to a long oscillatory shaft 14 which
extends approximately from the front to the
rear of the machine. A sector 15 (Figs. I,
II and III) is rigidly secured to the rear
end of shaft 14, and this sector 15 meshes

with teeth at the lower end of a long feeding lever 16, said lever being detachably secured to the typewriter by means of a pivot screw 17. F designates the platen carriage of the typewriter (Figs. I, III and VII), said carriage being adapted to travel back and forth in a straight horizontal line, and it may be actuated in response to the key operations, as is well understood in this art, the carriage 10 moving one step in response to each key operation. The rear portion of the platen carriage is provided with a long toothed horizontal bar 18. G designates pin-carrying clips straddling the toothed bar 18 and 15 adjustably mounted thereon. Each clip G is provided with a power transmission pin 19 adapted to cooperate with certain elements at the upper end of the long lever 16 for the purpose of transmitting movement 20 from the platen carriage to said long lever. Abutment fingers 20 and 21 at the upper end of lever 16 cooperate in a peculiar manner with the pins 19, as will be hereafter described, but it should be now understood 25 that the long lever 16 oscillates in response to movements of the platen carriage, and that motion is thus transmitted from the long lever 16 to the sector 15 at the rear of the machine, and thence through the long 30 inclined shaft 14 (Figs. I and II) to the sector 13, which meshes with the rack bar 5 on the master wheel carriage. Motion is thus transmitted from the traveling platen carriage to the master wheel carriage, so as 35 to advance the latter step by step in response to movements of the platen carriage.

When the platen carriage of the typewriter reaches a predetermined position, it begins to transmit movement to the means 40 for feeding the master wheel carriage, and after the master wheel passes entirely across the accumulator, the feeding means is disengaged from the platen carriage, permitting the latter to continue in motion without 45 advancing the master wheel. Attention is now directed to the means whereby the platen carriage is connected to and disconnected from the long feeding lever 16 at the rear of the typewriting machine. The 50 power transmission pins 19, carried by the platen carriage, form part of the means for connecting said carriage to the feeding lever 16. 22 designates a restoring spring tending to retain the lever 16 in engagement with 55 a stationary stop pin 23, shown in Figs. III and VII. The elongated abutment finger 21 is pivotally mounted on a pin 24 carried by the long lever 16, and shown in Figs. III, V and VII. This pivoted finger 21 extends 60 into the horizontal path of the traveling pins 19, so as to transmit movement from said pins to the lever 16. As shown most clearly in Figs. III and V, a spring 25 tends 65 to retain the upper portion of finger 21 in engagement with the upper portion of lever

16. When the finger 21 occupies the last mentioned position, it lies in the path of traveling pins 19.

The retaining finger 20 is pivoted at 26 to the extended upper end of lever 16, and this finger 20 is movable into the path of the traveling pins 19 so as to cooperate with the finger 21 in connecting the platen carriage to the long lever 16. A spring 27 tends to retain the finger 20 in the position shown by Fig. VII, wherein said finger engages a stop pin 28 on the long lever 16. However, when said lever 16 occupies its starting position (Fig. III), the finger 20 is displaced to locate its free end in an elevated position 70 entirely above the path of the traveling pins 19. At this time a finger 20' extending from the finger 20 engages an abutment screw 29, the latter being mounted in a stationary part 75 of the machine. When one of the traveling pins 19 strikes the finger 21 it begins to transmit movement to the long lever 16, and as this lever moves from its starting position 80 the finger 20' will pass from the abutment screw 29 (Fig. VII) and the spring 27 will 85 then move said finger 20 to the position shown by Figs. IV and VII, wherein the end of said finger 20 lies in the path of the traveling pins 19. Movement can then be transmitted in either direction from the pin 19 90 to the long lever 16, and under these conditions the latter cannot be accidentally thrown, or otherwise moved, independently 95 of the traveling pin 19.

When the master wheel passes entirely 100 across the accumulator, the elongated finger 21 is tripped to permit the spring 22 to restore the long lever 16. The means for tripping the abutment finger 21 comprises a stationary cam finger 30 extending into the 105 path of the upper portion of finger 21. When the finger 21 slides along the cam 30, as shown by dotted lines in Fig. IV, the upper end of said fingers is forced outwardly to a position beyond the path of the traveling 110 pin 19. The finger 21 is thus disengaged from the pin 19, and the spring 22 then quickly restores the long lever 16 to the starting position shown by Fig. III. It will now 115 be understood that a series of the traveling pins 19 can be mounted on the platen carriage, and that each pin will transmit movement to the long lever 16 whereby the master wheel carriage is actuated. When the first pin 19 of the series passes from the trippable 120 finger 21, the long lever 16 is restored to its starting position, and the trippable finger 21 then lies in the path of the second pin 19.

After a traveling pin 19 is disengaged 125 from the trippable finger 21, the platen carriage can continue in motion for ordinary typewriting, and when the platen carriage is eventually restored, the traveling pins 19 will pass idly across the trippable finger 21, merely moving the latter on its pivot 24 130

without actuating the long feeding lever 16. To understand this feature, it should be noted that the inner face of finger 21 is beveled to provide an inclined cam, as shown by Fig. IV. A pin 19 traveling to the right from the position shown in Fig. IV will engage the relatively thick edge of finger 21, but when the platen carriage is restored, the pins 19 will move to the left from the position shown in Fig. IV, and they will then strike the inclined inner face of the finger 21 so as to idly move said finger on its pivot 24.

Transmitting movement from the key levers 15 to the rotary master wheel.

The key levers 31 (Fig. I) form part of the typewriting machine, and they may be considered as the numeral key levers with which typewriting machines are ordinarily equipped, it being unnecessary to change the keyboard of the typewriting machine used with this calculating attachment. Each numeral key lever 31 is provided with an extension 32 (Fig. I) having a pin 33 through which motion is transmitted to the calculating machine, the extension 32 being rigidly secured to the key lever. Vertically guided slide bars 34 (Figs. I and II) are connected by means of levers 35 to the key extensions 32, each of said levers 35 being pivoted to the upper end of one of the slide bars 34 (Fig. I) and provided with a hook adapted to receive the pin 33 on one of the key extensions 32. These connecting levers 35 are used to transmit power from the numeral keys to the slide bars 34, and each of said levers may be disengaged from the pin 33 on a key lever extension. However, I do not deem it necessary to show or describe any means for disconnecting the levers 35 from the key extensions.

There are ten of the vertical slide bars 34 (Figs. I and II) representing the digits "0" to "9", inclusive, and each of these slide bars, excepting the bar associated with the "0" key, is provided with means for transmitting movement to an oscillatory digit wheel shaft 36. The slide bar 34 associated directly with the numeral "1" key will drive the digit wheel shaft 36 a distance corresponding to one step of the calculating operation, the slide bar 34 representing the digit "2" being adapted to drive said shaft 36 a distance of two steps, etc., the "9" key being adapted to drive said shaft nine steps.

To accomplish this each of the slide bars 34 representing the digits "1" to "9", inclusive, may be provided with a predetermined number of rack teeth adapted to mesh with a toothed digit wheel 37 (Figs. I and II), the digit wheels being rigidly secured to the digit wheel shaft 36. It will now be understood that the typewriter numeral keys representing digits "1" to "9", inclusive, may be used to actuate the slide

bars 34 whereby the digit wheel shaft 36 is actuated, and the degree of movement imparted to the digit wheel shaft will depend upon the value of the key from which motion is transmitted. Uniform strokes are imparted to the several digit keys and their slide bars 34, but the teeth on the slide bars are normally free of engagement with the digit wheels 37, and at the beginning of a key stroke the slide bars move idly until their teeth mesh with the digit wheels. It will therefore be understood that the digit wheels 37 are not necessarily uniform in diameter, and in practice the digit wheels 37 corresponding to the lowest numbers may be relatively large, as shown at the left side of Fig. II.

To restore the slide bars 34, a series of levers 38 is loosely mounted on a rod 39 (Figs. I and II), the forward end of each lever 38 being located between pins 40 on a slide bar 34. A restoring spring 41 is associated with each lever 38, as shown in Fig. I, so as to yieldingly retain the slide bars 34 in their elevated positions.

The means for transmitting movement from the digit wheel shaft 36 to the master wheel shaft 4 is shown in Figs. I and II. The digit wheel shaft 36 oscillates in response to movements of the toothed slide bars 34, but the master wheel shaft is driven continuously in only one direction during the adding operations. 42 designates a ratchet wheel fixed to the integer wheel shaft 36, and 43 designates a gear wheel loosely mounted on said shaft. A pawl 44, shown by dotted lines in Fig. I, engages the ratchet wheel 42 and is pivotally secured to the gear wheel 43. The train of gearing through which motion is transmitted comprises a large gear 45 meshing with the gear wheel 43, a smaller gear wheel 46 meshing with the large gear 45, as shown in Figs. I and II, and another gear wheel 47 meshing with the gear 46, said gear wheel 47 being fixed to the master wheel shaft 4, as shown in Fig. II. A pawl 48 (Fig. I) cooperates with the large gear wheel 45 to prevent retrograde movement of the train of gearing.

This train of gearing, including the ratchet and pawl 42 and 44 (Fig. I), transmits rotary movement to the master wheel shaft 4 in response to the oscillatory movements of the digit wheel shaft 36, and when the machine is in service the master wheel travels along the shaft 4, advancing step by step from one accumulator wheel to another, so as to successively actuate the different total wheels. For example, to introduce the numeral "29" into the accumulator, the "2" key is depressed while the master wheel registers with an accumulator wheel 3 in the tens order. The total wheel in the tens order is thus turned two steps, and the

master wheel is then driven by the platen lever E. 66 designates a spring tending to 70
carriage so as to pass to the units order. Thereupon the "9" key is depressed, with
the result of actuating the total wheel in the 5 units order, driving it nine steps.

Locking and unlocking devices.

To prevent operation of the calculating 10 mechanism when the master wheel occupies
certain positions, I have shown a locking 15 device including a universal locking plate
or bar 50 (Figs. I and II) adapted to co-
operate with all of the levers 38 to prevent
operation of the numeral keys and slide
bars 34. Each of these levers 38 extends
between two pins on a slide bar 34 (Fig. I)
so as to move with the slide bar. Each lever
38 is also provided with a depending stop
finger 51 adapted to cooperate with the
locking bar 50 for the purpose of prevent-
ing operation of the key actuated slide bars
34, thereby preventing the transmission of
movement from the numeral keys to the cal-
culating mechanism. The locking bar 50 is
20 rigidly secured to an oscillatory shaft 52
provided with a post 53 to which an unlock-
ing spring 54 is secured. The spring 54 tends
to shift the locking bar 50 from the paths
of stop fingers 51, thereby tending to un-
lock the mechanism. An operating arm, ex-
tending from the locking bar 50, is provided
with an operating finger 55 which cooper-
ates with certain devices whereby the lock-
ing bar 50 is shifted to lock and unlock the
30 mechanism. The operating finger 55 ap-
pears in Figs. I and II and also in Figs.
VIII to XI inclusive.

One of the devices cooperating with the
operating finger 55 is in the form of a bell
crank lever E pivoted at 56 to a stationary
bracket 57 and provided with arms 58 and
59 which are shown most clearly in Figs.
VIII to XI inclusive. 60 designates a lock-
ing spring connected to the arm 58 of bell
crank E, and tending to elevate said arm
58. It is to be understood that the locking
spring 60 is stronger than the unlocking
spring 54, so if the spring 60 is permitted
to elevate the lever arm 58, the latter will
50 act upon the operating finger 55 so as to
move the locking bar 50 into the paths of
stop fingers 51 as shown by Fig. I. In Figs.
VIII, IX and X, the lever arm 58 occupies
its elevated position, and the operating fin-
ger 55 cooperates with said arm 58 to retain
the locking bar 50 in its locked position,
shown by Fig. I. 61 designates a stop pin
engaged by the bell crank lever to limit the
movement thereof in one direction.

To lock the bell crank lever E in an inef-
fective position, shown by Fig. XI, I have
shown a latch device comprising a latch
arm 62 pivoted at 63 and provided with a
shoulder 64 adapted to be engaged by a
shoulder 65 on the lower end of bell crank

66 designates a spring tending to 70
retain the latch arm 62 in engagement with
the lower end of bell crank lever E. From
the foregoing it will be understood that the
bell crank lever E may be shifted from its
locking position shown by Fig. VIII to its
unlocking position shown by Fig. XI, and
when the bell crank lever reaches the last
mentioned position it will be retained there
by the spring actuated latch arm 62. 75

The means for imparting movement to the
bell crank lever E includes a pawl 67 piv-
oted to said bell crank and adapted to co-
operate with the segmental ratchet member
68 fixed to the long inclined shaft 14 80
through which motion is transmitted to the
master wheel carriage. A spring 69 tends
to force the pawl 67 into engagement with
ratchet member 68, as shown by Fig. IX.
Pawl 67 is provided with an inclined face 85
70 adapted to engage a stationary pin 71
for a purpose to be hereafter pointed out.
The operation of the ratchet 68 and pawl
67 may be generally understood by referring
to Fig. IX, wherein the pawl is engaged
with the ratchet and the bell crank lever
E and operating finger 55 are in their lock-
ing positions. If the ratchet 68 is moved
to the right from the position shown by
Fig. IX, a longitudinal movement will be
90 imparted to pawl 67 so as to actuate the bell
crank lever E, thereby shifting said bell
crank lever to the position shown by Fig.
XI, where it will be automatically locked
95 by the latch arm 62. When a longitudinal
motion is imparted to pawl 67, as just
pointed out, its inclined face 70 cooperates
100 with pin 71 with the result of elevating
the ratchet-engaging end of the pawl, and
when the spring actuated latch arm 62 is
thrown to the position shown by Fig. XI,
105 an extension 62' of said latch arm engages
said pawl to entirely disengage the pawl
from the ratchet, as shown by Fig. XI. The
bell crank E is thus released from operat-
110 ing finger 55 in response to the operation
of the ratchet and pawl, and after the pawl
has performed its function the bell crank
is latched in the position shown by Fig. XI
115 and the pawl is thrown to the inoperative
position shown in Fig. XI, where it is held
by the latch arm extension 62'. 120

Before describing the precise functions
of the ratchet and pawl, I will refer to an
intermittent locking member whereby the
locking bar 50 is intermittently shifted to
its locking position for the purpose of pre-
venting operation of the master wheel
while the latter is passing from one de-
nominal position to another, or from
one order to another. 125

F designates an intermittent locking mem-
ber in the form of a segment fixed to the
long inclined shaft 14 through which motion
is transmitted from the platen carriage to 130

the master wheel carriage. Teeth 72 and notches 73 are formed in the peripheral face of the locking member F. The operating finger 55, whereby locking bar 50 is actuated, overlies the peripheral face of the intermittent locking member F, and when said operating finger 55 lies in one of the notches 73, the locking spring 54 (Fig. I) is permitted to retain the locking bar 50 in a position beyond the paths of stop fingers 51, but when the operating finger 55 lies over one of the teeth 72, said finger 55 is in an elevated position and the locking bar 50 must therefore lie in the paths of stop fingers 51.

To understand the operation of these locking and unlocking devices, it should be borne in mind that the locking member F and the ratchet 68 are fixed to the oscillatory shaft 14 so as to move in accordance with movements of the master wheel carriage.

When the master wheel carriage occupies its starting position, or home position, shown by Fig. II, the lock controlling devices occupy the positions shown by Fig. VIII, and the key actuated slide bars 34 are thence locked through the medium of the locking bar 50. At this time the operating finger 55 which extends from the locking bar, is engaged by lever arm 58 (Fig. VIII) and the locking spring 60 acts upon said arm 58 to retain the operating finger 55 in an elevated position, thereby retaining the locking bar 50 (Fig. I) in the paths of stop fingers 51. When the master wheel B travels forwardly from its starting position so as to mesh with the first wheel 3 of the accumulator, the intermittent locking member F and ratchet 68 move in the direction indicated by an arrow in Fig. VIII. As a result, ratchet 68 engages pawl 67 so as to shift the bell crank E to its unlocking position where it is held by the latch arm 62, thereby permitting the operating finger 55 to engage the peripheral face of the intermittent locking member F. When the master wheel is in mesh with the first wheel of the accumulator, the first notch of the intermittent locking member F will register with the operating finger 55; thereby permitting said operating finger to move downwardly into said notch. The unlocking spring 54 (Fig. I) is then permitted to withdraw the locking bar 50 from the paths of stop fingers 51. From the foregoing description of the operation, it should be understood that the key actuated slide bars 34 are locked when the master wheel carriage occupies its starting position, and that said slide bars are automatically unlocked when the master wheel B meshes with the first wheel 3 of the accumulator.

I will now describe the manner in which the calculating machine is intermittently locked and unlocked as the master wheel

advances step by step from one wheel 3 to another. The wheels 3 and the master wheel B are shown in Figs. I and VI. The object is to prevent premature operation of the master wheel. I have already shown that the operating finger 55 lies in the first notch 73 when the master wheel registers with the first wheel 3 of the accumulator. To advance the master wheel from the first wheel 3 to the second wheel 3 motion is imparted to the long shaft 14 to which the intermittent locking member F is secured, and in response to a motion of this kind, one of the teeth 72 on locking member F will pass under the operating finger 55 so as to elevate said finger and thereby shift the locking bar 50 to its locked position. When the master wheel B is properly meshed with one of the accumulator wheels 3 (Fig. VI) the operating finger 55 lies in one of the notches 73 as indicated by Fig. XI, but when the master wheel travels from one wheel 3 to another, a tooth 72 on locking member F will pass under and elevate the operating finger 55 so as to move the locking bar 50 to its locked position. The master wheel advances step by step, as previously pointed out, and the notches 73 in locking member F correspond to the definite denominational positions of the master wheel, it being understood that locking member F advances in unison with the master wheel so as to lock the operating finger 55 in one of the notches 73 when the master wheel is positioned for actuation by the numeral keys. By locking and unlocking the calculating mechanism in this manner, I prevent premature operation of a key which would either cause the number to be introduced into the wrong order in the accumulator, or if the teeth of the master wheel B are wide enough to engage two wheels 3 at the same time, premature operation of the master wheel may result in operation of two wheels 3 at the same time.

The accumulator A as shown in Fig. II is provided with a space 75, and when the master wheel registers with this space, a period may be printed by the typewriter for the purpose of indicating a decimal point. Since no calculating operation is performed while the master wheel registers with space 75, the calculating machine should be locked, and the intermittent locking member F is provided with a relatively wide tooth 72' which engages the operating finger 55 when the master wheel registers with the decimal space 75.

The lock controlling device herein shown also causes the locking of the calculating mechanism during the return stroke of the master wheel carriage. I have already referred to the spring 10 (Fig. II) whereby the master wheel carriage is quickly restored to its starting position when its op-

erating means is released from the platen carriage, and this release occurs after the master wheel passes from the wheel of lowest order in the accumulator. To lock the calculating machine during the return stroke of the master wheel carriage, the bell crank lever E is shifted to the position shown by Fig. X, wherein it engages the operating finger 55 to locate the locking bar 50 in the paths of stop fingers 51. It is to be understood that while the master wheel carriage is moving forwardly, the bell crank lever E is held in the ineffective position shown by Fig. XI. 76 designates an abutment pin (Fig. X) carried by the locking member F and adapted to engage an abutment pin 77 on the latch arm 62. When the master wheel reaches its extreme forward position, the abutment pin 76 cooperates with abutment pin 77, as shown in Fig. X, to displace latch arm 62 from the bell crank E, thereby permitting the locking spring 60 to shift said bell crank to the locking position shown in Fig. X. During the return stroke of the master wheel carriage, the locking member F and ratchet 68 move in the direction indicated by an arrow in Fig. X, and the ratchet 68 travels idly under the pawl 67. When the master wheel finally reaches its starting position, the lock controlling devices occupy the positions shown in Fig. VIII.

Under some conditions, for example when the platen carriage is quickly shifted in response to the operation of a tabulating key, the master wheel carriage may be operated by the motion transmitted from one of the traveling pins 19 (Fig. III) on the rear of the platen carriage, and as the rapid motion of the platen carriage is continued, the other pin 19 may engage the finger 21 before the master wheel carriage is restored to its starting position. In this event, the master wheel carriage will be stopped in an intermediate position, instead of being permitted to make a full return stroke to its starting position. This may frequently happen when the platen carriage is provided with a series of the traveling pins 19 and also with a tabulating key permitting over-rapid motion of the platen carriage, and the master wheel carriage may be thus stopped in any of its intermediate positions instead of being permitted to return to the starting position. When this occurs, the calculating machine should be locked during the partial return of the master wheel carriage, and the mechanism should thereafter be unlocked in response to a forward motion of the master wheel carriage. Fig. IX shows the positions of the lock controlling devices when the master wheel is stopped in an intermediate position, without being permitted to complete its return stroke. The locking spring 60

(Fig. IX) then cooperates with bell crank E to retain the operating finger 55 in its locked position, and the pawl 67 engages one of the teeth on the ratchet 68. To advance the master wheel, the shaft 14 will be operated by the platen carriage and the ratchet 68 will therefore move in the direction indicated by an arrow in Fig. IX so as to impart a longitudinal movement to the pawl 67, thereby shifting the bell crank E to its unlocking position shown by Fig. XI, and permitting the latch arm 62 to retain said bell crank in this position. It will now be understood that the master wheel carriage may be stopped in any intermediate position while it is returning to its starting position, and when said carriage is thereafter advanced one step, the pawl 67 and bell crank E will be shifted from the positions shown by Fig. IX to the positions shown by Fig. XI. The bell crank lever E is thus displaced from its locking position to its unlocking position in response to the forward motion of the master wheel carriage.

The locking device and lock controlling devices herein disclosed prevent operation of the calculating mechanism when the master wheel is in its starting position, also during each forward step of the master wheel carriage and during the entire return stroke of the master wheel carriage. However, the calculating mechanism may be operated when the master wheel is properly positioned for actuation of the accumulator.

I claim:

1. In a calculating machine, an accumulator provided with an actuator and a denominational carriage movable step by step to change the denominational relation of the actuator to the accumulator, means for imparting a step by step movement to the denominational carriage, operating means whereby said actuator is driven to transmit motion to said accumulator, locking means for preventing actuation of said operating means, and an unlocking device adapted to unlock said locking means to permit actuation of said operating means, said locking means including an intermittent lock-actuating member movable step by step in accordance with movements of said means for imparting a step by step movement to said denominational carriage, and said intermittent lock-actuating member being ineffective when said denominational carriage is positioned for proper actuation of the accumulator.

2. In a calculating machine, an accumulator provided with an actuator and a denominational carriage movable step by step to change the denominational relation of the actuator to the accumulator, means for imparting a step by step movement to the denominational carriage, operating means whereby said actuator is driven to transmit

100

- motion to said accumulator, locking means for preventing actuation of said operating means, and an unlocking device adapted to unlock said locking means to permit actuation of said operating means, said locking means including an intermittent lock actuating member whereby said operating means is locked during each forward step of said denominational carriage, so as to prevent actuation of said operating means while said carriage is in motion, and said intermittent lock actuating member having a series of lock actuating teeth adapted to successively actuate the lock.
15. 3. In a calculating machine, an accumulator provided with an actuator and a denominational carriage movable step by step to change the denominational relation of the actuator to the accumulator, means for imparting a step by step movement to the denominational carriage, operating means including numeral keys whereby said actuator is driven to transmit motion to said accumulator, key locking means for preventing actuation of said numeral keys, and an unlocking device adapted to unlock said locking means to permit actuation of said numeral keys, said locking means including an intermittent lock actuating member whereby said numeral keys are locked during each forward step of said denominational carriage, so as to prevent operation of said keys while said carriage is in motion, and said intermittent lock actuating member being driven by said means for imparting a step by step movement to said denominational carriage.
4. In a calculating machine, an accumulator provided with an actuator and a denominational carriage movable step by step to change the denominational relation of the actuator to the accumulator, means for imparting a step by step movement to the denominational carriage, operating means including numeral keys whereby said actuator is driven to transmit motion to said accumulator, key locking means for preventing actuation of said numeral keys, and an unlocking device adapted to unlock said locking means to permit actuation of said numeral keys, said locking means including a stop device for preventing actuation of said numeral keys, yielding means tending to displace said stop device from its effective position, said locking means also including an intermittent actuating member whereby said stop device is forced to its effective position during each forward stroke of said denominational carriage, so as to prevent actuation of the keys while said carriage is in motion, and said intermittent actuating member being driven by said means for imparting a step by step movement to said denominational carriage.
5. In a calculating machine, an accumulator provided with an actuator and a denominational carriage movable step by step to change the denominational relation of the actuator to the accumulator, means for imparting a step by step movement to the denominational carriage, operating means including numeral keys whereby said actuator is driven to transmit motion to said accumulator, key locking means for preventing actuation of said numeral keys, and an unlocking device adapted to unlock said locking means to permit actuation of said numeral keys, said locking means including a stop device for preventing actuation of said numeral keys, yielding means tending to displace said stop device from its effective position, and an intermittent actuating member having a series of teeth whereby said stop device is forced to its effective position during each forward stroke of said denominational carriage, so as to prevent actuation of said numeral keys while said carriage is in motion, and said intermittent actuating member being driven by said means for imparting a step by step motion to said denominational carriage so as to move in synchronism with said carriage.
6. The combination of a typewriter having numeral keys and a platen carriage, calculating mechanism comprising an accumulator provided with an actuator and a denominational carriage movable step by step to change the denominational relation of the actuator to the accumulator, carriage driving means whereby a step by step motion is transmitted from said platen carriage to said denominational carriage, means whereby motion is transmitted from said numeral keys to said actuator, and means for preventing operation of said actuator while it is passing from one denominational position to another, the last mentioned means including a lock for said numeral keys and an intermittent lock actuating member driven by said platen carriage so as to move in synchronism with said denominational carriage.
7. The combination of a typewriter having numeral keys and a platen carriage, calculating mechanism comprising an accumulator provided with an actuator and a denominational carriage movable step by step to change the denominational relation of the actuator to the accumulator, carriage driving means whereby a step by step motion is transmitted from said platen carriage to said denominational carriage, means whereby motion is transmitted from said numeral keys to said actuator, and means for preventing operation of said actuator while it is passing from one denominational position to another, the last mentioned means including a lock for said numeral keys and an intermittent lock actuating member driven by said platen carriage so as to move in synchronism with said denominational carriage, and an unlocking member whereby said lock

is unlocked when said denominational carriage occupies its several denominational positions.

8. The combination of a typewriter having numeral keys and a main carriage, calculating mechanism comprising an accumulator provided with an actuator and a denominational carriage movable step by step to change the denominational relation of the actuator to the accumulator, carriage driving means whereby a step by step motion is transmitted from said main carriage to said denominational carriage, means whereby motion is transmitted from said numeral keys to said actuator, and locking means preventing operation of said numeral keys while said denominational carriage is returning to its starting position, said locking means comprising a lock operating member under the control of said main carriage.

9. The combination of a typewriter having numeral keys and a platen carriage, calculating mechanism comprising an accumulator provided with an actuator and a denominational carriage movable step by step to change the denominational relation of the actuator to the accumulator, carriage driving means whereby a step by step motion is transmitted from said platen carriage to said denominational carriage, means whereby motion is transmitted from said numeral keys to said actuator, and locking means preventing operation of said numeral keys while said denominational carriage is returning to its starting position, said locking means comprising a lock for the numeral keys, yielding means tending to retain said lock in its operative position, and a restraining means adapted to retain said lock in an inoperative position, said restraining means being under the control of said platen carriage.

10. The combination of a typewriter having numeral keys and a platen carriage, calculating mechanism comprising an accumulator provided with an actuator and a denominational carriage movable step by step to change the denominational relation of the actuator to the accumulator, carriage driving means whereby a step by step motion is transmitted from said platen carriage to said denominational carriage, means whereby motion is transmitted from said numeral keys to said actuator, and locking means preventing operation of said numeral keys while said denominational carriage is returning to its starting position, said locking means comprising a lock for the numeral keys, yielding means tending to retain said lock in its operative position, and a restraining means adapted to retain said lock in an inoperative position, said restraining means including a detent released by said platen carriage.

11. The combination of a typewriter hav-

ing numeral keys and a platen carriage, calculating mechanism comprising an accumulator provided with an actuator and a denominational carriage movable step by step to change the denominational relation of the actuator to the accumulator, carriage driving means whereby a step by step motion is transmitted from said platen carriage to said denominational carriage, means whereby motion is transmitted from said numeral keys to said actuator, and locking means preventing operation of said numeral keys while said denominational carriage is returning to its starting position, said locking means comprising a lock for the numeral keys, yielding means tending to retain said lock in its operative position, and a restraining means adapted to retain said lock in an inoperative position, said restraining means including a latch device and a traveling abutment driven by said platen carriage to release said latch device.

12. The combination of a typewriter having numeral keys and a platen carriage, calculating mechanism comprising an accumulator provided with an actuator and a denominational carriage movable step by step to change the denominational relation of the actuator to the accumulator, carriage driving means whereby a step by step motion is transmitted from said platen carriage to said denominational carriage, means whereby motion is transmitted from said numeral keys to said actuator, locking means comprising a movable stop device associated with said numeral keys and adapted to prevent operation thereof, and a lock actuating device comprising a spring whereby said stop device is shifted to its operative position, a latch device whereby said spring is rendered ineffective while said denominational carriage is moving forwardly, and means whereby said latch device is released upon the completion of the forward motion of the denominational carriage, so as to permit operation of said spring.

13. In a calculating machine, an accumulator provided with an actuator and a denominational carriage movable step by step to change the denominational relation of the actuator to the accumulator, carriage driving means for imparting a step by step movement to the denominational carriage, key controlled operating means whereby said actuator is driven to transmit motion to said accumulator, restoring means for returning said denominational carriage to its starting position, said restoring means permitting stoppage of said carriage in intermediate positions while it is returning to its starting position, locking means preventing operation of said actuator during the return movement of said carriage, and an unlocking device whereby said locking means is unlocked, said unlocking device including an automatic un-

locking member effective when said carriage moves forwardly from any of said intermediate positions.

14. In a calculating machine, an accumulator provided with an actuator and a denominational carriage movable step by step to change the denominational relation of the actuator to the accumulator, carriage driving means for imparting a step by step movement to the denominational carriage, key controlled operating means whereby said actuator is driven to transmit motion to said accumulator, restoring means for returning said denominational carriage to its starting position, said restoring means permitting stoppage of said carriage in intermediate positions while it is returning to its starting position, locking means preventing operation of said actuator during the return movement of said carriage, and an unlocking device whereby said locking means is unlocked, said unlocking device including a traveling actuating member movable step by step in accordance with movements of said carriage and an unlocking member adapted to be driven by said traveling actuating member, said unlocking member and its actuating member being effective when said carriage moves forwardly from any of said intermediate positions.

15. In a calculating machine, an accumulator provided with an actuator and a denominational carriage movable step by step to change the denominational relation of the actuator to the accumulator, carriage driving means for imparting a step by step movement to the denominational carriage, key controlled operating means whereby said actuator is driven to transmit motion to said accumulator, restoring means for returning said denominational carriage to its starting position, said restoring means permitting stoppage of said carriage in intermediate positions while it is returning to its starting position, locking means preventing operation of said actuator during the return movement of said carriage, and an unlocking device whereby said locking means is unlocked when said carriage moves forwardly, said unlocking device including a traveling actuating member movable in accordance with movements of said carriage and provided with a series of actuating elements corresponding to said intermediate positions of the carriage, and an unlocking member adapted to be driven by each of said actuating elements so as to become effective when said carriage moves forwardly from any of said intermediate positions.

16. In a calculating machine, an accumulator provided with an actuator and a denominational carriage movable step by step to change the denominational relation of the actuator to the accumulator, carriage driving means for imparting a step by step move-

ment to the denominational carriage, key controlled operating means whereby said actuator is driven to transmit motion to said accumulator, restoring means for returning said denominational carriage to its starting position, said restoring means permitting stoppage of said carriage in intermediate positions while it is returning to its starting position, locking means preventing operation of said actuator during the return movement of said carriage, and an unlocking device whereby said locking means is unlocked when said carriage moves forwardly, said unlocking device including a ratchet and pawl through which the unlocking movement is transmitted, and said ratchet and pawl being driven by the means for imparting movement to said carriage.

17. In a calculating machine, an accumulator provided with an actuator and a denominational carriage movable step by step to change the denominational relation of the actuator to the accumulator, carriage driving means for imparting a step by step movement to the denominational carriage, key controlled operating means whereby said actuator is driven to transmit motion to said accumulator, restoring means for returning said denominational carriage to its starting position, said restoring means permitting stoppage of said carriage in intermediate positions while it is returning to its starting position, locking means preventing operation of said actuator during the return movement of said carriage, and an unlocking device whereby said locking means is unlocked when said carriage moves forwardly from any of said intermediate positions, said unlocking device including a traveling actuating member movable in accordance with movements of said carriage and provided with a series of actuating teeth corresponding to said intermediate positions of the carriage, and an unlocking member in the form of a pawl adapted to be driven by each of said teeth so as to become effective when said carriage moves forwardly from any of said intermediate positions.

18. The combination of a typewriter having numeral keys and a platen carriage, calculating mechanism comprising an accumulator provided with an actuator and a denominational carriage movable step by step to change the denominational relation of the actuator to the accumulator, means whereby motion is transmitted from said numeral keys to said actuator, carriage driving means whereby a step by step motion is transmitted from said platen carriage to said denominational carriage, said carriage driving means being effective when the platen carriage is in different fields, restoring means for returning said denominational carriage when said platen carriage passes from one of said fields, said restoring means permit-

ting stoppage of said denominational carriage in intermediate positions while the latter is returning to its starting position, locking means whereby said numeral keys are locked during the return movement of said denominational carriage, and an unlocking device whereby said locking means is unlocked in response to a forward motion of said denominational carriage, said unlocking device including an unlocking member effective when the forward motion begins at any of said intermediate positions.

19. The combination of a typewriter having numeral keys and a platen carriage, calculating mechanism comprising an accumulator provided with an actuator and a denominational carriage movable step by step to change the denominational relation of the actuator to the accumulator, means whereby motion is transmitted from said numeral keys to said actuator, carriage driving means whereby a step by step motion is transmitted from said platen carriage to said denominational carriage, said carriage driving means being effective when the platen carriage is in different fields, restoring means for returning said denominational carriage when said platen carriage passes from one of said fields, said restoring means permitting stoppage of said denominational carriage in intermediate positions while the latter is returning to its starting position, locking means whereby said numeral keys are locked during the return movement of said denominational carriage, and an unlocking device whereby said locking means is unlocked in response to a forward motion of said denominational carriage, said unlocking device including a traveling actuating member movable step by step in accordance with movements of said denominational carriage, and an unlocking member adapted to be driven by said traveling actuating member when said carriage moves forwardly from any of said intermediate positions.

20. The combination of a typewriter having numeral keys and a platen carriage, calculating mechanism comprising an accumulator provided with an actuator and a denominational carriage movable step by step to change the denominational relation of the actuator to the accumulator, means whereby motion is transmitted from said numeral keys to said actuator, carriage driving means whereby a step by step motion is transmitted from said platen carriage to said denominational carriage, said carriage driving means being effective when the platen carriage is in different fields, restoring means for returning said denominational carriage when said platen carriage passes from one of said fields, said restoring means permitting stoppage of said denominational carriage in intermediate positions while the latter is returning to its starting position, lock-

ing means whereby said numeral keys are locked during the return movement of said denominational carriage, and an unlocking device whereby said locking means is unlocked in response to a forward motion of said denominational carriage, said unlocking device including a traveling actuating member driven in one direction by said platen carriage and restored by said restoring means, said traveling actuating member having a series of actuating elements corresponding to said intermediate positions of the denominational carriage, and an unlocking member adapted to be driven by each of said actuating elements so as to become effective when said denominational carriage moves forwardly from any of said intermediate positions.

21. The combination of a typewriter having numeral keys and a platen carriage, calculating mechanism comprising an accumulator provided with an actuator and a denominational carriage movable step by step to change the denominational relation of the actuator to the accumulator, means whereby motion is transmitted from said numeral keys to said actuator, carriage driving means whereby a step by step motion is transmitted from said platen carriage to said denominational carriage, said carriage driving means being effective when the platen carriage is in different fields, restoring means for returning said denominational carriage when said platen carriage passes from one of said fields, said restoring means permitting stoppage of said denominational carriage in intermediate positions while the latter is returning to its starting position, locking means whereby said numeral keys are locked during the return movement of said denominational carriage, and an unlocking device whereby said locking means is unlocked in response to a forward motion of said denominational carriage, said unlocking device including a ratchet through which the unlocking movement is transmitted, and said ratchet being driven in one direction by said platen carriage and in the opposite direction by said restoring means. 85 90 95 100 105 110

22. The combination of a typewriter having numeral keys and a platen carriage, calculating mechanism comprising an accumulator provided with an actuator and a denominational carriage movable step by step to change the denominational relation of the actuator to the accumulator, means whereby motion is transmitted from said numeral keys to said actuator, carriage driving means whereby a step by step motion is transmitted from said platen carriage to said denominational carriage, said carriage driving means being effective when the platen carriage is in different fields, restoring means for returning said denominational carriage when said platen carriage passes 130

from one of said fields, said restoring means permitting stoppage of said denominational carriage in intermediate positions while the latter is returning to its starting position, locking means whereby said numeral keys are locked during the return movement of said denominational carriage, and an unlocking device whereby said locking means is unlocked in response to a forward motion of said denominational carriage, said unlocking device including a toothed ratchet member and a pawl cooperating therewith to transmit the unlocking movement, a spring tending to retain said pawl in engagement with said ratchet member, and means for retaining said pawl in an inoperative position after it has been actuated by said ratchet member.

23. The combination of a typewriter having numeral keys and a platen carriage, calculating mechanism comprising an accumulator provided with an actuator and a denominational carriage movable step by step to change the denominational relation of the actuator to the accumulator, carriage driving means whereby a step by step movement is transmitted from said platen carriage to said denominational carriage, said driving means comprising a plurality of travelers carried by said platen carriage and a transmission member through which motion is transmitted from said travelers to said denominational carriage, said travelers being separated from each other so as to successively transmit movement while said platen carriage is in different fields, restoring means adapted to return said denominational carriage when said transmission member is released from one of said travelers, means for transmitting movement from said numeral keys to said actuator, locking means whereby said numeral keys are locked during the return movement of said denominational carriage, and an unlocking device whereby said locking means is unlocked in response to a forward motion of said denominational carriage, said unlocking device including a ratchet actuated unlocking member adapted to become effective when said denominational carriage passes from one denominational position to another.

24. The combination of a typewriter having numeral keys and a platen carriage, calculating mechanism comprising an accumulator provided with an actuator and a denominational carriage movable step by step to change the denominational relation of the actuator to the accumulator, carriage driving means whereby a step by step motion is transmitted from said platen carriage to said denominational carriage, means whereby motion is transmitted from said numeral keys to said actuator, and locking means for preventing operation of said

actuator while said denominational carriage is passing from one denominational position to another and also while it is returning to its starting position, the last mentioned means including an intermittent lock actuating member whereby said numeral keys are locking during each forward step of said denominational carriage and another lock actuating member whereby said keys are locked during the return movement of said denominational carriage, and both of said lock actuating members being driven by said platen carriage.

25. In a calculating machine, an accumulator provided with an actuator and a denominational carriage movable step by step to change the denominational relation of the actuator to the accumulator, carriage driving means for imparting a step by step movement to the denominational carriage, key controlled operating means whereby said actuator is driven to transmit motion to said accumulator, restoring means for returning said denominational carriage to its starting position, said restoring means permitting stoppage of said carriage in intermediate positions while it is returning to its starting position, locking means preventing operation of said actuator while said denominational carriage is passing from one denominational position to another and also while said carriage is returning to its starting position, and an unlocking device whereby said locking means is unlocked in response to any forward movement of said carriage, said locking means and unlocking device being under the control of said carriage driving means.

26. The combination of a typewriter having numeral keys and a platen carriage, calculating mechanism comprising an accumulator provided with an actuator and a denominational carriage movable step by step to change the denominational relation of the actuator to the accumulator, carriage driving means whereby a step by step motion is transmitted from said platen carriage to said denominational carriage, means whereby motion is transmitted from said numeral keys to said actuator, locking means adapted to prevent operation of said numeral keys, said locking means including an intermittent lock actuating member movable step by step in response to movements of said platen carriage, so as to become effective in response to each forward step of the denominational carriage, and an unlocking device including a ratchet and pawl driven by said platen carriage so as to unlock said locking means in response to a forward motion of said platen carriage.

27. The combination of a typewriter having numeral keys and a platen carriage, calculating mechanism comprising an accumulator provided with an actuator and a de-

- nominal carriage movable step by step to change the denominational relation of the actuator to the accumulator, carriage driving means whereby a step by step motion is transmitted from said platen carriage to said denominational carriage, means whereby motion is transmitted from said numeral keys to said actuator, a stop device adapted to prevent operation of said numeral keys, a spring tending to move said stop device to an inoperative position, an oscillatory operating member having a succession of operating teeth whereby said stop device is repeatedly shifted to its operative position, said oscillatory operating member being driven by said carriage driving means so as to operate said stop device during each forward step of said denominational carriage, a trippable spring actuated operating member whereby said stop device is rendered effective during the return movement of said denominational carriage, and a resetting device for restoring said trippable operating member, said resetting device including a ratchet and pawl driven by said carriage driving means so as to become effective in response to a forward motion of said platen carriage. 50
28. The combination of a typewriter having numeral keys and a platen carriage, calculating mechanism comprising an accumulator provided with an actuator and a denominational carriage movable step by step to change the denominational relation of the actuator to the accumulator, carriage driving means whereby a step by step motion is transmitted from said platen carriage to said denominational carriage, means whereby motion is transmitted from said numeral keys to said actuator, a stop device adapted to prevent operation of said numeral keys, a spring tending to move said stop device to an inoperative position, an oscillatory operating member having a succession of operating teeth whereby said stop device is repeatedly shifted to its operative position, said oscillatory operating member being driven by said carriage driving means so as to operate said stop device during each forward step of said denominational carriage. 55
29. In a machine of the class described, the combination with a series of adding keys, and an adding mechanism including denomination selecting mechanism movable back and forth, of key locking means operated by the movement of the denomination selecting mechanism in one direction to lock the keys, and means for holding the keys locked during the return movement of said mechanism. 60
- In testimony that I claim the foregoing I hereunto affix my signature.

EDWARD C. SCHINKE.
